UNITED STATES PATENT OFFICE.

STEPHEN A. DAVIS AND ROBERT BLAKE, OF NEWARK, NEW JERSEY.

SCREW-SWAGING MACHINE.

SPECIFICATION forming part of Letters Patent No. 280,723, dated July 3, 1883.

Application filed December 9, 1882. (No model.)

To all whom it may concern:

Be it known that we, STEPHEN A. DAVIS and ROBERT BLAKE, citizens of the United States, both residing at Newark, in the county 5 of Essex and State of New Jersey, have invented certain new and useful Improvements in Screw-Swaging Machines, of which the following is a description in such full, clear, concise, and exact terms as to enable any one 10 skilled in the art to which it appertains or with which it is most nearly connected to make and use the same, reference being had to the accompanying drawings, making part of this specification, and to the figures and letters of 15 reference marked thereon.

Reference being had to said drawings, Figure 1 is a side elevation of a machine embracing and including our invention; Fig. 2, a front elevation thereof, and Fig. 3 a top view, Figs. 20 4, 5, and 6 being parts in detail, as will be hereinafter more fully explained.

The construction and operation of this machine will be understood from the following description, the points of novelty being pointed 25 out in the claims concluding this specification.

Similar letters of reference represent corresponding parts of the different figures of the drawings.

The frame is shown by A, upon the side of 30 which a cam-shaft, e, is placed, and supported in suitable journal-bearing, J, and upon the top of said frame a main driving-shaft, B, is placed, carried in the journal-bearing K', said shaft being fitted with a fast and loose pulley, 35 C and C', and also a bevel-wheel, D, by which the power is applied to drive the machine.

In front of the frame a spindle, E, is set in the journal-bearing K. Upon this spindle a bevel-wheel, N, is placed to gear into the wheel 40 D, by which the spindle is made to rotate about its own axis. This spindle has not only a rotating motion, but it has also a vertical motion in the line of its axis. The upward motion of this spindle is imparted to it by a screw-thread, I, working in a half-nut, R. This half-nut is operated by means of a lever, Q, and a cam, Q', on the shaft e, and a spring, Q'', connecting the lever to a pin in the frame, the nut being pressed forward by the action of the 45 cam upon the lever, and held against the thread 50

L until the time comes for the spindle to fall, when the cam releases the lever and the spring Q'' draws it back, disengaging the nut and leaving the spindle to fall, as shown by Fig. 6; but to overcome the friction of the machinery 55 on the spindle and to make it fall promptly, a yoke-lever, F, is applied to its top by means of a grooved collar, G. This lever is fulcrumed at i, and has a roller, i', in its opposite end, acting against a cam, H, by which the spindle is not 60 only made to fall promptly and quickly, but is also prevented from slamming and hammering upon the journals in its descent. In the end of said spindle a screw-driver, f, is set, and also a chuck, T T, the screw-driver being set in 65 the center of the spindle and the chuck mortised in the periphery and pivoted at t. The screw-driver of course rotates with the spindle, and the chuck opens and closes upon the head of the screw, the screw-driver having a 70 spring behind it to prevent injuring the head of the blank. The chuck T is made to grip the head of the screw by means of a grooved collar, O', operated by means of a forked lever, O, the opposite end of which works in the 75 cam P, the cam operating to force the end of the lever up and the collar down upon the chuck, and to hold it there until the time comes to release the screw. The cam then releases the long end of the lever, and the spring 80 r draws up the collar, releasing the chuck, which in its turn is forced open by means of a spring placed in the spindle between the jaws of the chuck. This spring is not shown in the drawings, but may be of any suitable construction adapted to the work.

Fixed to the frame of the machine, and centered directly under the axis of the spindle, a die-box, U, is placed, inclosing a set of swaging-dies. A horizontal sectional view of this 90 die-box and the dies is shown by Fig. 4 upon an enlarged scale. The box consists of a ring, U, made to reciprocate about its own axis by means of a cam, U'', on the shaft e, acting against an arm, U', and by a spring, U''', the 95 cam throwing the ring forward and the spring pulling it back the moment the arm is released by the cam. The swaging-dies consist of rollers U', the edges of which are made in the form desired to swage the required style of 100

thread on the screw. These dies are set in blocks of steel *b*, mortised in a disk of metal and radiating from the center or axis of the box. The inner ends of these blocks of steel 5 carry the roller-dies upon suitable pivots or center bearings, and their outer ends are sloped, cam-like, all in one direction, and against each of them a cam set-screw, *j*, is placed through the ring *U*. By these means it will 10 be seen that when the cam *U*" strikes the arm *U*' all of the die-blocks *b* are pressed forward by the screws *j* upon the screw-blank to be swaged; but the moment the cam releases the arm the spring *U*"" draws the arm back, releasing 15 the blocks *b*, which in their turn are forced apart by the springs *h*, acting against a projection, *V*, on the side of each of the blocks in the manner shown. The spring *u* is an auxiliary spring to assist the spring *U*"" in moving back the ring *U*, as described.

Directly under the center of the die-box and the axis of the spindle *E* is placed a receiving-socket, *W*. This socket is supported upon a lever, *Y*, and is guided by the sleeve *X*. It 25 has an upward motion imparted to it by means of a spring, *Z*, and a downward motion imparted to it by means of a cam, *d*, through the lever *Y*, fulcrumed at *a*.

Directly under the die-box, and in close 30 proximity to the top of the socket *W*, a leader, *c*', is set, coming from a hopper. (Not shown in the drawings.) The object of this leader is to carry the screw-blanks *c*' from the hopper to the socket *W*, by which they are fed into the 35 machine, a blank dropping into the top of the socket every time it is drawn down by the cam, the jar of the machine at every rotation of the cam being sufficient to shake one of the blanks off of the leader into the socket. All 40 of the rotating cams, it will be seen, are placed on the shaft *e*, and the motion is transmitted to this shaft by means of a worm-screw, *M*, acting upon a worm-wheel, *S*, and a bevel-wheel placed on the shaft *I*, to gear into a corresponding wheel on the shaft *e*, the worm *M* 45 being carried by the hub *K*" of the wheel *N*.

The operation is as follows: The cam *d* draws down the socket *W*, a screw-blank, *c*', drops into it. At that instant the dies are opened 50 by the spring *U*"". The spring *Z* then draws the socket up, carrying the screw-blank between the dies. The spindle then falls by the action of the cam *H*, and the chuck *T* and screw-driver *f* grip the head of the screw. 55 The dies then close by the action of the cam *U*", and the nut *R* is moved forward by the cam *Q*' and engages the thread *L*. The spindle rises with a left-hand rotating motion, forming the thread on the screw *T* as it rises 60 and backs out of the die. The screw is then released from the chuck by the action of the cam *P* and spring *r*, and drops into a small pan, (not shown in the drawings,) by which it is removed and succeeded by another blank, 65 as before.

In the operation of the machine the spring *Z* performs two functions. It not only draws the socket *W* up to the die, but also permits it to yield to the spindle in its downward motion in case the screw-blank is a trifle too long, 70 thus allowing the screw-driver to find its hold in the nick of the screw-head without danger of breaking it or tearing the head of the screw.

In the construction of the above-described machine the gearing-wheels are proportioned 75 with reference to each other, so as to cause the spindle to make about thirty-six revolutions to one of the cam-shaft; but this proportion of speed may be modified as circumstances may require.

We claim and desire to secure by Letters Patent—

1. In a screw-swaging machine, the combination of spindle *E*, having a chuck, *T*, and collars *G* and *O*', and a rotating and reciprocating motion, a set of swaging-dies, *b* *b* *b*', having an opening and closing motion, a feeding-socket, *W*, having a reciprocating motion, a cam-shaft, *e*, having a rotating motion, and fitted with cams *H*, *Q*', *P*, *U*", and *d*, a set of 90 cam connecting and operating levers, *F*, *Q*, *O*, *U*', and *Y*, a set of retractile springs, *U*"" *Z*', a connecting-nut, *R*, a driving-shaft and pulleys, *B* *C*, a pair of gear-wheels, *N* *D*, a connecting-shaft, *I*, between the spindle and cam-shaft, fitted with a worm-wheel, *S*, acting into a worm, *M*, and a bevel-wheel gearing into a corresponding wheel on the cam-shaft, all of the several parts being supported upon a suitable frame, *A*, and made to coact substantially 100 as described.

2. In a screw-swaging machine, the combination of a set of opening and closing rotating swaging-dies, *b* *b* *b*', a feeding-socket, *W*, a supporting-lever, *Y*, a rotating cam, *d*, and a 105 spring, *Z*, the several parts coacting substantially as described.

3. In a screw-swaging machine, the combination of a set of opening and closing rotating swaging-dies, a spindle fitted with a screw-driver and chuck, a rotating cam, *P*, and a lever, *O*, connecting the chuck and cam, the several parts coacting substantially as described.

4. In a screw-swaging machine, a set of 115 rotating swaging-dies, *b* *b* *b*', set in metal cam-blocks *b* *b* *b*, radiating from a common center, combined with springs *h*, and inclosed in a reciprocating ring fitted with cam-screws *j* *j*', the several parts coacting substantially as described.

5. In a screw-swaging machine, the combination of a rotating cam, *Q*', a spindle, *E*, having a screw-thread, *L*, cut in its periphery, a nut, *R*, to open and close on the thread, a lever, *Q*, and spring *Q*" to operate the nut, the whole coacting substantially as described.

6. In a screw-swaging machine, the combination of a gravitating spindle, *E*, having a groove-collar, *G*, a rotating cam, *H*, a connect- 130

ing-lever, F, a half-nut, R, and a screw, L, the several parts coacting substantially as described, for the purpose specified.

7. In a screw-swaging machine, the combination of a cam-shaft, e, a screw-holding spindle, E, a connecting-shaft, I, a worm-wheel, S, and a worm, M, working on the spindle E, the shafts I and e being fitted with gear-wheels,

and the several parts coacting with the rotating swaging-dies, substantially as described. 10
